UNITED STATES PATENT OFFICE

CHARLES A. TURNER, OF MOUNT CARMEL, ILLINOIS.

NON-REFILLABLE BOTTLE.

1,106,598.

Specification of Letters Patent. Patented Aug. 11, 1914.

Application filed April 30, 1913. Serial No. 764,668.

To all whom it may concern:

Be it known that I, CHARLES A. TURNER, a citizen of the United States, residing at Mt. Carmel, in the county of Wabash, State of Illinois, have invented certain new and useful Improvements in Non-Refillable Bottles; and I do hereby declare the following to be a full, clear, and exact description of the invention, such as will enable others skilled in the art to which it appertains to make and use the same.

This invention relates to improvements in non-refillable bottles, and has for its object to so construct an article of this type that it will be impossible to refill the same after the original contents thereof have been emptied.

A further object of the invention is to so construct a bottle of this type which can be manufactured at a minimum cost, simple in construction, and one in which the neck would have to be broken to refill the same, thus indicating to the purchaser that the bottle does not contain its original contents.

With these and other objects in view, this invention resides in the novel features of construction, formation, combination and arrangement of parts to be hereinafter more fully described, claimed and illustrated in the accompanying drawing, in which:

Figure 1 is a vertical sectional view through the bottle. Fig. 2 is a sectional view on line 2—2 of Fig. 1. Fig. 3 is a detail perspective view of one of the guards. Fig. 4 is a sectional view on line 4—4 of Fig. 1.

Referring to the drawing, the numeral 1 designates a bottle having the neck 2, the lower end of which is provided with a valve seat 3. Formed interiorly of the neck 2 are annular shoulders 4, 5 and 6, the same being spaced apart, and arranged one above the other. Mounted in the neck 2 for slight vertical movement is a stem 7, preferably formed from glass, and having formed upon its upper end a disk 8, the same being of a diameter slightly less than the neck 2 so that liquid can pass therearound when the bottle is inverted, and it is desired to pour the contents therefrom. Adapted to coact with the valve seat 3 is a disk 9, the same being smaller than the disk 8, and has

formed upon its upper surface a projection 7' and upon its under surface a lug 10 which engages the cork plug 11, the same being conical in shape and is adapted to engage 55 the valve seat 3 when the bottle is in an upright or partly upright position so that liquid cannot be placed in the bottle.

Guards 12, 13 and 14 are operable in the neck 2 and are formed from disks of sheet 60 metal, the same being bent concavo-convex in cross section. Each guard is formed with a central aperture 15, the apertures of the guards 12 and 13 being engaged by the stem 7, while the aperture of the guard 14 is engaged by the projection 7', whereby all of the guards remain in spaced relation. The guards are held upon their respective co-operating elements by molten glass. The guards are of course connected to the stem 70 7 and projection 7' previous to the insertion of the same in the bottle neck 2. It is obvious that when the stem 7 is placed in the neck 2 and forced downwardly the guards will contract sufficiently so that the guard 75 12 will pass the shoulder 4, and the guards 13 and 14 will pass the shoulders 5 and 6, after which the guards expand so that when the bottle is inverted to pour the contents therefrom the rims of said guards will engage 80 their respective shoulders, and whereupon the stem 7 will move downwardly with the extension 7', thus permitting the plug 11 to disengage the seat 3, the movement of the stem being arrested when the edges of 85 the guards contact with their respective shoulders. Each guard is provided with a plurality of slots 16 and notches 16', and through which the liquid passes when the bottle is inverted. The valve plug 11 is 90 held in engagement with the seat 3 upon placing the cork 17 in the bottle neck which rests upon the disk 8.

What is claimed is:

A bottle of the class described having a 95 valve seat formed in its neck, a plurality of annular shoulders formed interiorly of said neck, a stem adapted for movement in the neck, a disk mounted in the neck and adapted to coact with said seat, said disk having a 100 projection formed thereon a plurality of guards connected to the stem, a single guard

carried by said projection, said guards being arranged one above the other and in spaced relation, slots formed in said guards, said guards being concavo-convex and adapted to have their edges contact with the shoulders when the bottle is inverted, and the disk disengages said seat.

In testimony whereof, I affix my signature, in the presence of two witnesses.

CHARLES A. TURNER.
